UNITED STATES PATENT OFFICE.

ADOLF REISSE, OF VIENNA, AUSTRIA-HUNGARY.

TYPE-WRITING MACHINE.

1,110,346.

Specification of Letters Patent. Patented Sept. 15, 1914.

Application filed April 30, 1914. Serial No. 835,399.

To all whom it may concern:

Be it known that I, ADOLF REISSE, a subject of the Emperor of Austria-Hungary, residing at Burggasse 10, Vienna, II, Austria-Hungary, have invented certain new and useful Improvements in Type-Writing Machines, of which the following is a specification.

The object of the present invention is to prevent the tapping noise on the paper in typewriting machines and to reduce the noise of operation to such an extent that it ceases to be disturbing, without, however, deleteriously affecting the lightness of touch, impression and view of the typed matter. To this end the mechanism serving to actuate the type is disposed in an entirely inclosed housing but the type and paper carriers are arranged outside said housing. The operative connection between the mechanism disposed inside the closed housing and the type carriers outside the latter is effected by a member passing directly or indirectly through the housing. The tapping noise on the paper is prevented by reducing the long movement of a rotating striking member to a short travel, and then allowing it to actuate the above mentioned member projecting through the wall of the housing.

The invention is illustrated in the accompanying drawing, in which:

Figure 1 is a diagrammatic longitudinal section, and Fig. 2 a cross section of the machine. Figs. 3, 4, 5, 6 and 7 show various forms of striking mechanism by way of example.

In Fig. 1, 1 indicates the housing of the machine, 2 the key levers, 3 a bar arranged transversely underneath the key levers 2, said bar being fixed to the arms 4 and pivoted at 5. The pull rod 6 connects one arm 4 with the toothed segment 8 rotatable at 7, said segment engaging with a pinion 9 on the shaft 10 (Fig. 2). On the shaft 10, which is mounted in bearings 11 and 12, is fixed the striking disk 13 (Figs. 1 and 2). On the striking disk 13 is mounted the roller 14 (Figs. 1 and 2). The double armed lever 16, which is journalled on the shaft 15 and forked at its upper end, acts on the gudgeon 17 of the rod 18. The rod 18 passes through the closed housing of the machine and is provided with a cranked part 19, in which the laminated type cylinder 20 with

types 20^a are free to move. The shaft 21 of the type cylinder projects through the housing 1, the driving and adjusting mechanism of the type carrier being disposed inside the closed housing. 22 is the paper roller mounted in a slide. The carriage rack 23 meshes with the pinion 24 fixed on the shaft 25. The latter projects through the housing 1, so that the entire shift mechanism of the carriage is inclosed in the closed 65 housing.

The function is as follows: When a key is depressed, the bar 3, rod 6, segment 8, roller 15 and striking member 13 move in the direction indicated by the arrows. The lever 16 remains stationary (roller position I-II) until the roller runs up the lower arm of the said lever 16. During this period the type carrier 20 is set. From position II the lever 16 moves in the direction indicated by arrow *a*, and the rod 18 in the direction of arrow *a'*, whereby the adjusted plate of the type cylinder 20 is moved out of the periphery of the latter until the type is impressed on the platen (roller position III). The position II of roller 14 clearly shows that the latter runs tangentially up the lower arm of lever 16, thereby preventing a sudden impingement of roller 14 on the lever 16. As the key 2 returns to 85 its original position all the parts move in the opposite directions to those indicated by the arrows until they assume their original positions.

Roller position III shows that the roller 90 at the end of the pressure acts vertically to the center of the lever 16, so that there is no braking action between the roller and lever. The release of the pressure after the impression thus occurs practically without frictional loss. This is of great importance for a light stroke, as any jamming action has to be overcome by powerful spring action which is associated with a heavy key touch. The tapping noise on the paper is avoided 100 by the type bar only having to move a very short distance before making the impression. If this movement were produced by direct leverage from the key to the type bar there would be no time left for the setting 105 of the type cylinder and on the other hand there would be no force for impression. It is only the proportion of the mass acceleration of the rotating striking member (13) to the leverage of roller (14), increased by 110

the leverage of the arms of the lever 16, which results in the striking member exerting a powerful push at the last part of its movement. A good view of the typed matter is insured by the type carrier and paper carrier being disposed outside the housing, and by the fact that when no type has been operated, the upper edge of the type cylinder 20 (Fig. 1) is disposed below the line of writing. The type cylinder is raised and brought into the writing position by the depression of the keys. The shape of the transmitting member 18—which may pass directly or indirectly through the casing—and whether said member passes direct through the housing or indirectly, for instance inside the shaft 21 of the type carrier, is immaterial to the invention, as is also the form of striking member 13 adopted, which may be a disk or lever.

Fig. 3 shows a striking device in which the striking member is a double armed lever 26 which acts with a short arm 27 on the bar 28. The lever 26 is actuated by the key through the medium of pull bar 29 and lever 30.

Fig. 4 shows the arrangement between the striking lever 31 and bar 32 of a bell crank lever 33 whereby greater leverage is afforded.

Fig. 5 shows a further modification, in which the striking lever is substituted by a striking disk, and the bell crank by a double armed lever 35. The hereinbefore described arrangements have a swinging striking member. Figs. 6 and 7 show an arrangement in which the striking member constantly rotates in the same direction. The striking lever 37 fixed to the shaft 36 (Fig. 6) rotates in the direction indicated by the arrow a^2 and is provided with a roller 38. The lever 40 pivoted at 39 acts on the bar 41. The shaft 36 is carried by bearings 42, 43 and is moved axially by the key lever 45 through the medium of the bell crank 46. 46 is a fixed stop. During the rotation (Fig. 6) the lever 37 is able to pass by the stop 46, said lever being pushed sidewise with the shaft 36. As soon as the impression has been made the shaft 36 is moved in the opposite direction, the roller 38 slides off lever 40 and the lever 37 abuts against the stop 46. (position II of roller 38).

What I claim as new is

1. A typewriting machine with a closed housing, operating mechanism inside the housing and a type carrier and paper carrier outside the housing, and an independent member projecting through the closed housing and as a transmitting member between the operating mechanism inside the closed housing and the type carrier outside.

2. A typewriting machine with a closed housing, a striking member rotatable about an axle inside the housing, a type carrier

outside the housing and a member passing through the closed housing and as a transmitting member between the striking member and type carrier.

3. A typewriting machine with a closed housing, a type carrier outside the housing, and a member projecting through the closed housing and cranked outside, said member serving as a transmitting member between the operating mechanism inside the casing and the type carrier.

4. A typewriting machine with a closed housing, a striking member inside the housing, a transmitting member projecting through the housing, levers in the housing between the striking member and transmitting member, and a type carrier outside the closed housing.

5. A typewriting machine with a closed housing, a type carrier outside the housing and operating mechanism inside the housing, an independent member between the operating mechanism and type carrier and projecting through the housing, a striking member in the housing and a pressure lever having arms of unequal length between the striking member and the member projecting through the housing wall.

6. A typewriting machine with a closed housing, an outside type carrier, a transmitting member projecting through the housing wall, a rotary striking member inside the housing, pressure lever between the striking member and transmitting member, the running up point of the rotating striking member on the pressure lever being at a tangent to the arc described by the striking member.

7. A typewriting machine with a closed housing, a transmitting member projecting through the housing wall, a rotary striking member in the housing, a pressure lever between the rotary striking member and the transmitting member and friction reducing members between the striking member and pressure lever.

8. A typewriting machine with a closed housing, a rotary striking member, toothed gearing for the striking member, a transmitting member projecting through the housing, and levers between the transmitting member and the striking member.

9. A typewriting machine with a closed housing and type carrier outside the housing, openings in the housing for the key levers and for a transmitting member to the type carrier, type levers, and connecting members between the type levers and striking member in the housing in conjunction with levers between said striking member and the transmitting member projecting through the housing.

10. A typewriting machine with a closed housing and type carrier outside the housing, openings in the housing for the key levers and for a transmitting member to the

type carrier, key levers, and a common cross bar underneath the key levers, and connecting members between the key levers and striking members inside the housing in conjunction with levers between the striking member and the transmitting member projecting through the housing wall.

In testimony whereof I affix my signature in presence of two witnesses.

ADOLF REISSER.
